COOLING UNIT FOR REFRIGERATING MACHINES

Lee S. Chadwick, Shaker Heights Village, and Marc Resek and Theodore B. Focke, Cleveland Heights, Ohio, assignors to Perfection Stove Company, Cleveland, Ohio, a corporation of Ohio

Application April 20, 1933, Serial No. 667,014

15 Claims. (Cl. 62—95)

This invention has to do with improvements in and relating to the evaporator or cooling unit of artificial refrigeration apparatus or machines.

The class of evaporator to which the invention especially pertains is that having associated with it a brine tank or the like for stabilizing the temperature of the refrigeration or food compartment and freezing space, it being well understood that in refrigeration apparatus or machines, the temperature of the evaporator rises during certain phases in the cycle of operation, as during the heating-condensing period of each cycle of operation of refrigerating machines of the intermittent absorption type; and unless a suitable "holdover" means is provided, this rise in temperature causes ice in the freezing space to melt and the food compartment to warm up to an undesirable degree.

Among the more general objects of our invention are the provision of a very efficient, strong and durable evaporator that is relatively simple of construction and economical of manufacture, the same being, desirably, in the nature of a shelf or support for one or more ice trays; and the combination, with such an evaporator, of a tank or receptacle containing a suitable brine or other cold storage substance having a stabilizing effect on the temperature of the surrounding atmosphere, said tank or receptacle being preferably removable, for one reason, to facilitate cleaning.

To promote sanitation as well as for the sake of appearance it is customary to coat the parts of the cooling unit that are susceptible to such treatment with a vitreous enamel or like material, and such coating, as is well known, is fragile and therefore chips easily and is readily fractured by distortion or expansion of the surface to which it is applied.

More specific objects of our invention are to provide a brine tank or receptacle for use with the evaporator of refrigeration apparatus or machines that makes use of the latent heat of fusion of a congealing substance; which tank or receptacle is desirably coated with vitreous enamel or the like and, to avoid distortion or expansion, contains a non-eutectic solution that will not freeze into a solid mass within the possible temperature range of the apparatus; to provide a tank or receptacle of the aforesaid nature that is so constructed, and is supplied with solution in such quantity, that a space within the tank or receptacle is provided for the expansion of the solution as it tends to solidify, and such space maintained substantially uniform throughout the

entire top portion of the receptacle to the end that strains or stresses will not be so concentrated within limited areas as to cause distortion of the vessel or expansion of the surface thereof with consequential cracking of the enamel; and to provide a tank or receptacle that cooperates with the evaporator in such manner as to render its attachment to and removal from the same especially convenient. In this connection it may be pointed out that a further purpose in making the tank or receptacle removable is that of enabling the same to be readily replaced, should it become damaged through any cause, without having to dismantle or disturb any of the other parts of the apparatus.

The foregoing objects, with others hereinafter appearing, are obtained in the embodiment of the invention illustrated in the accompanying drawings wherein Fig. 1 is a fragmentary sectional side elevation of an intermittent absorption refrigerating machine incorporating our improved cooling unit; Fig. 2 is a partial front elevation of the cooling unit on a scale somewhat enlarged over that of Fig. 1, all following views being on the larger scale; Fig. 3 is a central, vertical, longitudinal section through the cooling unit and the parts of the machine thereabove; Fig. 4 is a transverse section on the line 4—4 of Fig. 3; Fig. 5 is a top plan view and Fig. 6 a bottom plan view of the evaporator, proper, parts being broken away to better reveal the construction; Fig. 7 is a central vertical longitudinal section through the evaporator; Fig. 8 is a transverse section on the line 8—8 of Fig. 5; Fig. 9 is a top plan view of the brine tank or receptacle removed from the evaporator; Fig. 10 is a central vertical longitudinal section through the same; and Fig. 11 is a transverse section on the line 11—11 of Fig. 9.

In Fig. 1, the body portion of the cabinet of the refrigerating apparatus or machine is designated 1 and consists of the usual lagged or insulated walls surrounding the refrigeration or food compartment 2 that is closed at the front by a door 3. Applied to the upper end of the body portion 4 is a top 4 that incorporates a base frame 5, from which is supported, by brackets 6, a receiver 7 that is shown in the form of a cylindrical tank having bulged ends. The receiver is sustained within and spaced from the walls of a metal shell 8 having a depending boss 9 through which a tubular connection 10 of the receiver depends.

As previously stated, the machine illustrated in part in Fig. 1 is of the intermittent absorption type and leading from the top rear portion of

the receiver is a conduit 11 which returns the refrigerant gas to the generator-absorber end of the system (not shown) during the cooling-evaporating period of a cycle of operation. The space 5 surrounding the receiver 7 within the shell 8 and top 4 is filled with a suitable insulating material 12.

Welded at 15 to the lower end of the connection 10 of the receiver is the rim of a cup or distributing head 16 that forms a part of the evaporator and is, in effect, a continuation of the connection 10. Extending laterally and forwardly from the lower portion of the cup or distributing head 16 are loops 17 of tubing (Figs. 5 to 8), it 15 being apparent especially from Fig. 7 that each loop communicates with one side of the cup 16 near the bottom thereof and extends laterally and thence forwardly therefrom, gradually rising as it progresses and then returns on a continued 20 upward incline to where it again joins the forward side of the cup at an elevation appreciably above the former end. The loops 17 and the bottom portion of the cup 16 are encased within a casting of zinc, aluminum or other suitable metal 25 which will be referred to hereinafter as the body 18. This body is preferably in the nature of a shelf, being flat on top and having a transverse rib 20 at its forward end whose front surface is inclined upwardly and forwardly and having, at 30 its opposite end, a boss 22 that surrounds the lower portion of the cup 16 and incorporates at its rear a depending stop 23. On its underneath surface, the body 18 has ribs 24 that encase the loops 17 (Fig. 8).

35 A sleeve 25 is interposed between a shoulder of the aforesaid boss 9 and an opposed part of the evaporator body 18 and surrounds the adjacent ends of the connection 10 and cup 16, the sleeve being held in place by the reduced lower 40 end of said boss that fits snugly within the same, and being filled with suitable insulation.

Without going into the details of the refrigerating apparatus or machine, it may be explained briefly that refrigerant condensate is delivered to the receiver and evaporator during the heating-condensing period of a cycle of operation through a conduit 27 (Fig. 3), and during the early stage of such period, any absorbent condensate that is present in the evaporator is returned to the 45 generator-absorber end of the system through a liquid return tube 28. For a full disclosure of the construction and operation of an intermittent absorption refrigerating apparatus of the kind in which our present improvements are shown incorporated, reference may be had to the patent 50 of D. Forbes Keith, No. 1,816,975, dated August 4, 1931. During the heating-condensing period, the evaporator and receiver become charged with liquid anhydrous refrigerant, the same standing 55 within the receiver to a level near the top thereof, and during the cooling-evaporating period, this refrigerant gradually gasifies and returns through the conduit 11 to be re-absorbed by the weak solution in the generator-absorber end of the system, during which time heat is abstracted from 60 the atmosphere of the refrigeration or food compartment 2, lowering the temperature of said compartment sufficiently to preserve foodstuffs placed therein. The temperature in the immediate vicinity of the evaporator drops below freezing 65 so that water within one or more trays 30 (Fig. 1) that is or are placed upon the shelf-like body 18 of the evaporator freezes solid. At this point it may be explained that, due to the inclination of the loops 17, the refrigerant is caused

to circulate through the loops, thus increasing the efficiency of the evaporator.

To protect the ice within the freezing space above the evaporator against melting, and also to better stabilize the temperature of the refrigeration or food compartment 2, during the heating-condensing period when relatively warm liquid refrigerant is collecting in the evaporator and receiver, the evaporator has associated with it a tank or receptacle 33 which contains a cold storage substance or solution 34 to about the level shown in Fig. 4. This tank or receptacle is an elongated vessel whose body portion 35 extends beneath and laterally beyond the body 18 of the evaporator and up and about the opposite sides thereof in the form of opposed legs 36 that have inwardly directed shoulders 37 on their inner sides for engagement over the lateral edges of the body 18, the tops of said legs being connected together and intercommunicating through a flat tube 38 (see Figs. 3, 4, 9, 10 and 11). At its forward end the body portion 35 of the tank or receptacle 33 has an upwardly extending lip 39 which is downwardly and rearwardly inclined on its inner side to correspond to the angular inclination of the forward end of the evaporator body, said lip substantially concealing said body from view when the door of the refrigerator is open. Adjacent its rear end, the top wall of the body portion of the tank or receptacle 33 has a depression 40 which accommodates the lower end of the boss 22 of the evaporator body, and when the vessel is slid lengthwise over said body, the rear end of the tank or receptacle strikes the stop 23 to arrest further movement of the vessel, while the lip 39 and the forward wall of the depression 40 of the tank are slightly spaced from the adjacent portions of the evaporator body thereby to protect the vitreous enamel or like coating of the tank or receptacle from injury.

The solution 34 that is contained within the tank or receptacle 33 is of a non-eutectic nature and is preferably composed of the following ingredients in about the proportions mentioned:

	Per cent by weight
Water	94
Glycerine	4
Tri-sodium phosphate	2

Such a solution we find very satisfactory. Within the possible temperature range of the apparatus, this solution will not freeze solid, and when it congeals at the lowest temperature of the apparatus it is mushy and might be compared with relatively soft ice cream. When subjected to much lower temperatures the ice formed is not as dense or hard as water ice, but has about the consistency of well frozen ice cream. A characteristic of the solution is that its freezing point decreases progressively as it congeals. In contradistinction to a eutectic solution, which freezes solid at a given temperature, the non-eutectic solution freezes in part as the temperature lowers. As the solution reaches the freezing point of water, a part of the water freezes out, leaving a stronger solution in the interstices between the frozen particles. As the temperature continues to lower, more water freezes out, leaving a still stronger solution, the frozen particles always being separated by the stronger solution, thus preventing any considerable pressure in any one direction. As the process of partial solidification progresses, the solution expands and is displaced upwardly into the vacant portions at

the tops of the legs 36 of the tank or receptacle, the air pressure in the opposed legs being equalized through the cross tube 38. The essential purpose of the cross tube is to take care of a 5 possible situation in which the tank is removed from the evaporator and placed on its side so that the solution would fill the lower leg. (Now considering the structure in the absence of the cross tube 38) the air from such leg would gradually 10 bubble up through the solution to the upper leg and then when the tank is replaced the liquid would be air bound in the one leg to practically the top thereof. When the liquid would later congeal it might impose such strains upon the 15 adjacent portion of the tank as to cause it to bulge and crack the enamel. Such a situation is avoided by the presence of the tube 38.

The advantages arising from the removability of the tank are ease of cleaning and facility of 20 replacing the tank in case it becomes damaged through any cause without having to disturb any of the parts or joints of the refrigeration apparatus or machine.

Having thus described our invention, what we 25 claim is:

1. An evaporator for refrigeration apparatus comprising a distributing head, tubing in looped form communicating therewith and extending therefrom in a substantially horizontal plane, 30 said tubing being solely supported by said head, and a rigid body of metal encasing the tubing and the portion of the head wherewith it communicates, the same serving as a shelf for the support of an object to be chilled.

35 2. An evaporator for refrigeration apparatus comprising a distributing head, tubing in looped form communicating therewith and extending therefrom in a substantially horizontal plane, and a shelf-like body of heat conducting material enclosing the tubing and having a substantially flat top surface, the underneath surface of said body having ribs within which the convolutions of the tubing are embedded.

3. An evaporator for refrigeration apparatus 45 comprising a distributing head, tubing in looped form communicating with the head and extending therefrom in a substantially horizontal plane, the opposite ends of the loop being connected with said head at different elevations and the tubing being gradually inclined upwardly from the lower to the higher end, and a shelf-like body of 50 heat conducting material encasing the tubing, the same having a substantially flat top surface and being of variable thickness above said tubing 55 to compensate for the difference in inclination between the latter and said top surface.

4. An evaporator for refrigeration apparatus comprising a distributing head, loops of tubing having one of their ends communicatively connected to said head at one elevation and their opposite ends similarly connected to the head at a higher elevation, the tubing being gradually inclined upwardly from the lower to the higher ends, and a cast metal body encasing the loops and 60 having a substantially flat top surface, the underneath surface of the body having ribs for the accommodation of the convolutions of the loops.

5. A cooling unit for refrigeration apparatus 65 comprising, in combination, an evaporator in the nature of a horizontal body serving as a shelf for the support of an object to be chilled, and a receptacle having opposed guiding portions for slid- 70 able engagement with the lateral edges of the evaporator, said receptacle containing a cold stor- 75 age substance and having an open space above the

evaporator for the accommodation of said object.

6. A cooling unit for refrigeration apparatus comprising, in combination, an evaporator in the nature of a horizontally disposed, relatively flat body, and a closed receptacle designed for slid- 5 able engagement endwise over the evaporator and having portions extending beneath and up along the opposite sides of the same, the opposite side portions of the receptacle a material distance 10 above the evaporator being communicatively connected together so as to leave an object receiving space above the evaporator, and a body of cold storage substance within the receptacle.

7. A cooling unit for refrigeration apparatus 15 comprising, in combination, a substantially horizontal relatively flat shelf-like body having passageways extending therethrough for refrigerant, and a receptacle designed to be slidably engaged endwise over the evaporator, the same extending 20 crosswise beneath the evaporator and up the opposite sides thereof and thence inwardly to provide shoulders that engage over the lateral edges of the evaporator, the receptacle having a lip portion that practically conceals the evaporator 25 and the evaporator having a stop for limiting the sliding movement of the receptacle with respect to the evaporator.

8. A cooling unit for refrigeration apparatus comprising, in combination, a cup-like member, 30 a metallic body encasing the lower end of said member and containing passageways communicating therewith, the body having a depending boss beneath said member and a stop extending 35 downwardly from the rear thereof, the opposite end of the body having a transverse rib whose forward side is inclined upwardly and forwardly, and a receptacle for slidable engagement endwise over the body, the same having a horizontal portion for disposition below the body and side portions that 40 extend upwardly along the sides of the body, said side portions being projected inwardly above the top plane of the body to form shoulders for engagement therewith along the lateral edges of the body, the horizontal portion of the receptacle 45 having a depression for the accommodation of the aforesaid boss and having an upwardly projecting lip for the concealment of the transverse rib of the body, the receptacle being adapted to engage the aforesaid stop to prevent contact between said lip and rib and between the forward side of said depression and the boss, the receptacle being coated with a fragile material and containing 50 a cold storage solution.

9. A cooling unit for refrigeration apparatus 55 comprising, in combination, a cup-like member, a metallic body encasing the lower end of said member and containing passageways communicating therewith, the body having a depending boss beneath said member and a stop extending 60 downwardly from the rear thereof, the opposite end of the body having a transverse rib whose forward side is inclined upwardly and forwardly, and a receptacle for slidable engagement endwise over the body, the same having a horizontal portion 65 for disposition below the body and side portions that extend upwardly along the sides of the body, said side portions being projected inwardly above the top plane of the body to form shoulders for engagement therewith along the lateral edges of the body, the horizontal portion of the receptacle having a depression for the accommodation of the aforesaid boss and having an upwardly projecting lip for the concealment of the transverse rib of the body, the receptacle being 70 75

adapted to engage the aforesaid stop to prevent contact between said lip and rib and between the forward side of said depression and the boss, the receptacle being coated with a fragile material 5 and containing cold storage substance, the top portions of the opposite sides of the receptacle being communicatively connected together above the body.

10. In refrigeration apparatus, the combination of a receiver, an evaporator situated a material distance therebelow, a tubular connection between the receiver and evaporator, a shell enclosing the receiver and having a boss surrounding the tubular connection, a sleeve enclosing and spaced from the tubular connection and interposed between the boss and evaporator, and insulating material filling the shell about said receiver and the space between the sleeve and tubular connection.

20. 11. A cooling unit for refrigeration apparatus comprising, in combination, an evaporator, and a closed receptacle for application thereto and that is readily removable therefrom for replacement and cleaning purposes, the same being 25 coated with fragile material and containing a non-eutectic solution that will partially congeal at temperatures attained during the operation of the apparatus.

12. A cooling unit for refrigeration apparatus 30 comprising, in combination, an evaporator, and a closed receptacle for application thereto, the same being coated with fragile material and con-

taining a solution of water, glycerine and tri-sodium phosphate.

13. A cooling unit for refrigeration apparatus comprising, in combination, an evaporator, and a closed receptacle for application thereto, the same being coated with fragile material and containing a solution of 94% water, 4% glycerine, and 2% tri-sodium phosphate, by weight. 5

14. A cooling unit for refrigeration apparatus comprising, in combination, an evaporator, and a closed receptacle for application thereto that extends beneath the evaporator and up along each side thereof, the upper ends of the opposed sides of the receptacle being communicatively connected together, the receptacle containing a 15 non-eutectic solution to within an appreciable distance of the top thereof.

15. In refrigeration apparatus, the combination of a receiver, an evaporator situated a material distance therebelow, a tubular connection 20 between the receiver and evaporator, a shell enclosing the receiver and having an opening for the accommodation of the tubular connection, a sleeve enclosing and spaced from the tubular connection and interposed between the shell and 25 evaporator, and insulating material filling the shell about said receiver and the space between the sleeve and tubular connection.
